UNITED STATES PATENT OFFICE

2,438,537

KNOT

Arthur Dewey Carter, Gastonia, N. C.

Application October 3, 1945, Serial No. 620,083

1 Claim. (Cl. 28—78)

1

This invention relates to an improved knot and more especially to a knot adapted to be employed in the joining together of yarn, thread, and the like used in the textile field such as the tying of parted ends in weaving, winding, reeling, and in various textile operations during the processing of the yarns and the use of the same in the manufacture of finished goods.

Heretofore when cotton and wool were largely used as the fibers from which threads, yarns, and the like were manufactured, the ordinary weaver's knot or chicken head knot would suffice to hold the ends together when they parted in a weaving or other operation. However, in the present day, when nylon, regenerated cellulose in filament form, and other filament yarns are used, they do not offer sufficient friction to prevent knots from parting when ends are joined together by the conventional knots heretofore employed. It is therefore necessary to employ an improved knot for filamentary yarns to keep the same from parting under the tension imparted to the same in weaving, and in other operations.

It is, therefore, an object of the invention to provide a knot for uniting two ends of yarn which will not slip and become parted.

Some of the objects of the invention having been stated, other objects will appear as the description proceeds when taken in connection with the accompanying drawings, in which:

Figure 1 is a view showing two ends of a strand in the position they occupy during the first stage of tying a knot;

Figure 2 is a view of two strands in the second stage of tying the knot;

Figure 3 is a view of two strands in the third stage of tying the knot;

Figure 4 is a view showing the two strands in the fourth stage of tying the knot;

Figure 5 is a view showing the two strands in the fifth stage of tying the knot;

Figure 6 is a view showing the two strands in the sixth stage of tying the knot;

Figure 7 is a view similar to Figure 6 but showing the knot beginning to be tightened;

Figure 8 is a view similar to Figure 7 but showing the knot in a further stage of being tightened;

Figure 9 is a reverse view of Figure 8;

Figure 10 is an enlarged view of the knot as shown in Figure 8;

Figure 11 is an enlarged view of the knot as shown in Figure 9.

Referring more specifically to the drawings, the numerals 10 and 11 represent the two ends

2

of a strand which may have parted and which it is desired to secure together by a suitable knot. It may represent that 10 is the exhausted end of one package of yarn and 11 is the beginning end of another package of yarn which are desired to be knotted together. In any event, the two ends 10 and 11 represent usually two identical or similar strands which are adapted to be united in a knot.

10 Of course, this knot is described as being tied by hand, but it can also be tied by suitable knot-tying mechanisms. The first step in the tying of the knot is to cross the strand 10 over the strand 11 as at 9, and the second step is then 15 to move the strand 10 underneath and across strand 11 as at 12 to provide a right angular portion in the strand 10 as it crosses the strand 11 at right angles. The next step is the reversing of the strand 10 to form a completed loop 13 and passing the end of the strand 10 rearwardly 20 along side the free end of strand 11 and over the strands 10 and 11 as at 14.

The next step, then, is to move the strand 11 across and over the strand 10 as at 15. The next 25 step, then, is to carry the end of strand 11 below the free end of strand 10 and below the main portion of strand 10 as indicated at 16. The next step, then, is to bring the free end of strand 11 up above the strand 10 and above its end portion 30 as at 20 and 21 and below the strand 11 as at 17. With the knot thus formed, it is ready for applying opposed tension to the main portion of strands 10 and 11 to begin tightening the knot.

In Figure 7, we see this partially accomplished 35 by opposite pull applied to the main portions of the two strands 10 and 11 to bring the knot into closer relation. In Figure 8, this tension has been such as to completely assemble the knot to a very tightly formed knot and, thus, the knot 40 is complete except that the tail portions 18 and 19 will be severed close to the knot so that this knot will pass through various types of textile machinery without interfering in any way with the machinery. The knot may be pulled into 45 a tighter relation than shown in Figures 8 to 11, inclusive.

It is thus seen that a knot is provided whereby the various portions of the knot will bind against each other and firmly grip the same and prevent slippage even of filamentary yarn, which is very slick.

In the drawings and specification there has been set forth a preferred embodiment of the invention, and although specific terms are employed, they are used in a generic and descriptive

sense only, and not for purposes of limitation, the scope of the invention being defined in the claim.

I claim:

A knot for uniting two strands of yarn together in which the first and second strands are alined with each other and with their ends pointing in opposite directions, the first strand having its end passing across and above the second strand and then crosswise beneath the second strand and being doubled back upon itself above both the second strand and the first strand and the other strand having its free end crossed above the free end of the first strand, the second strand having its free end passed be-

5
10
15

neath the free end of the first strand and the main portion of the first strand and then the second strand having its free end passed above the body portion of the first strand and above the free end portion of the first strand and beneath the body portion of the second strand to thus form a knot in which the second strand bites both the main body portion and the free end of the first strand and in which the first strand surrounds the second strand and has the body portion and the free end thereof disposed around the second strand to thus provide a non-slipping knot.

ARTHUR DEWEY CARTER.
